MARKING, SQUEEGEEING, AND DEVELOPING MACHINE

William F. Huck, Richmond Hill, N. Y., assignor
to R. Hoe & Co., Inc., New York, N. Y., a corporation of New York

Application October 5, 1937, Serial No. 167,452

16 Claims. (Cl. 101—33)

This invention is directed to marking, squeegeeing and developing machines for photogravure or rotogravure printing, and, particularly, to improved mechanism for applying the register marks and securing the sensitized carbon tissue in accurate position upon the peripheral portion of the printing cylinder and for developing and etching the cylinder preparatory to printing.

In multicolor photogravure printing, wherein 10 a number of separate impressions are made in different colors, it is essential that accurate register be provided for. A separate cylinder is employed for each color, and the images or matter that are etched on the several cylinders must be 15 located very accurately in order to insure proper register in printing. In the preparation of the form cylinders for photogravure printing, the form for the images or printing matter is printed on a sheet of sensitized tissue from which the 20 image or printed matter is subsequently transferred to the surface of the form cylinder and etched into the cylinder surface. Register marks are drawn on the tissue sheet in the margin space, and a marking mechanism is provided 25 for marking circumferential and longitudinal lines on the peripheral surface of the cylinder, and when the register marks on the tissue sheets are accurately aligned with the marks on the cylinder surface, the tissue sheets are then correctly 30 positioned to insure that the images or printing matter are transferred therefrom to the correct location on the printing cylinder surface to produce accurately registered printing.

After the edge of the sensitized carbon sheet 35 or tissue has been aligned with register marks on the printing cylinder, it is then necessary to secure the entire sheet in accurately registered position upon the cylinder, and to treat the carbon tissue so that it may be stripped from the cylinder leaving the image bearing film or emulsion adhering to the cylinder surface, preparatory to the usual developing and etching operations. Therefore, an object of this invention is to provide improved means for wetting the cylinder-engaging face of the tissue preparatory to 40 securing it in accurate register upon the printing surface of the cylinder and the removal of its flexible backing.

Another object of this invention is to provide 50 means whereby the pressure or squeegee roller is so located with relation to the peripheral portion of the form cylinder, when operably engaging the tissue on the cylinder, as to provide a valley or trough to retain fluid on the cylinder surface for wetting the sensitized surface of the 55

tissue to aid in the application of the tissue to the cylinder and in the ready removal of the flexible backing of the carbon tissue.

A further object of this invention is the provision of improved means for readily and rigidly securing the index or form cylinder drive wheel to the shaft of the form cylinder in accurate concentric relation to the cylinder and shaft axis.

An additional object of this invention is to provide a marking, squeegeeing and developing machine 10 in which a composite multi-receptacle developing and etching tray or fountain housing is movably mounted for positional reversal relative to the peripheral surface of a photogravure form cylinder which is rotatably mounted in the ma- 15

chine frame.

Another object of this invention is to provide 20 a marking, squeegeeing and developing machine in which the squeegee or pressure roller is counter balanced for movement to and from operable contact with a form cylinder rotatably mounted in the machine, and, also, the provision of means for operably disconnecting the counter balance from the pressure or squeegee roller during a 25 phase of its operable engagement with the form cylinder.

Another object of this invention is to provide 30 a marking, squeegeeing and developing machine which rotatably supports a form cylinder, and includes a cooperable counter balanced pressure or squeegee roller arranged to be moved to and from operable engagement with the form cylinder through the instrumentality of foot operated components.

Another object of this invention is to provide 35 a marking, squeegeeing and developing machine which is constructed and arranged to rotatably support an intaglio or rotogravure form cylinder, and has a composite developing and etching fountain or tray suitably counter balanced for 40 manual movement to and from the form cylinder.

Another object of this invention is to provide 45 a marking, squeegeeing and developing machine which includes novel marking mechanism that is constructed and arranged, for cooperable engagement with the peripheral portion of a form cylinder rotatably supported in the machine frame, in a manner to obviate chattering or vibratory movement of the marking tool during its marking operation either circumferentially or 50 longitudinally along the peripheral surface of the form cylinder.

Another object of this invention is to provide 55 a marking, squeegeeing and developing machine in which an intaglio or photogravure form cyl-

inder is mounted for rotary movement in spaced yokes, and each yoke having a movable hinged component constructed and arranged for quick and convenient locking and release.

- 5 Another object of this invention is to provide a marking squeegeeing and developing machine, which is constructed and arranged for rotatably supporting an intaglio or rotogravure form cylinder, the machine including a pressure or squeegee 10 roller mounted for operable engagement with the form cylinder and operably supported for positional adjustment to accommodate cylinders of different diameters and to engage each cylinder in predetermined positional relationship.
- 15 It is also an object of this invention to provide a marking, squeegeeing and developing machine, for intaglio or rotogravure printing cylinders, of generally improved construction, whereby the device will be simple, durable and inexpensive in 20 construction, as well as convenient, practicable, serviceable, and efficient in its use.

With the foregoing and other objects in view, which will appear as the description proceeds, the invention resides in the combination and arrangement of parts and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detailed description of an improved marking, squeegeeing and developing machine for rotogravure or photogravure form cylinders will now be given in connection with the accompanying drawings forming a part of the specification, wherein:

40 Figure 1 is a side elevation of a combined marking, squeegeeing and developing machine having a photogravure printing cylinder rotatably mounted therein;

45 Figure 2 is a similar view but showing components of the machine in a different phase of operation;

Figure 3 is a vertical sectional view of the machine, parts being broken away and parts appearing in elevation;

50 Figure 4 is a plan view, parts appearing in section;

Figure 5 is a vertical detailed sectional view taken through the locking and releasing members of the cylinder bearing yoke;

55 Figure 6 is a horizontal detailed sectional view taken on the line 6-6 of Figure 5, showing the components in locking position;

Figure 7 is a similar view, but showing the components in unlocked or release position;

60 Figure 8 is a fragmental plan view depicting the quick locking and releasing device for securing the hinged yoke member to the machine frame;

Figure 9 is a transverse sectional view taken 65 through the reversible fountain or tray unit;

Figure 10 is a side elevation of the reversible fountain or tray unit;

Figure 11 is a detailed fragmental longitudinal sectional view taken on the line 11-11 of Figure 70 9 and depicting the supporting and positional securing components for the fountain or tray unit;

Figure 12 is an enlarged longitudinal sectional view depicting the index or cylinder drive wheel locking arrangement;

75 Figure 13 is a longitudinal sectional view taken

through the clamping sleeve of the index wheel locking device;

Figure 14 is an end view thereof, and

Figure 15 is a diagrammatic view depicting the 5 cooperative relationship between the pressure or squeegee roller and the form cylinder, the offset position of the squeegee roller relative to the form cylinder being somewhat exaggerated to better illustrate the invention.

Referring to the drawings, in which similar 10 reference characters designate corresponding parts, there is depicted an improved marking, squeegeeing and developing machine for intaglio rotogravure or photogravure form cylinders, and the machine includes marking and registering 15 mechanism of the type disclosed in Patent No. 1,832,255, granted November 17, 1931, to J. F. Springstead, and in the Gustav A. Friess, Patent No. 2,074,218, granted March 16, 1937, except that the marking mechanism herein disclosed incorporates improvements which will be hereinafter 20 described. This machine includes a frame 12 supported on a base 13 which is provided with a drain basin or receptacle 14 having a bottom 15 which slants toward a drain outlet opening 16. 25 The frame is provided with spaced supporting rails 17 and a superstructure 18 including spaced supporting uprights or frame members 19. The lower spaced portions of the slide members of the superstructure 19 are mounted on the spaced 30 supporting rails 17, and each side member of the superstructure includes a fixed arcuate yoke member 20 having a movable arcuate yoke member 21 hinged thereto, as indicated at 22, and the lower portion of each movable hinged yoke member 21 is secured to the rail 17 by a quick locking and releasing mechanism 23, which will be explained in detail hereinafter.

Each composite bearing yoke 20-21 is arranged to receive therein antifriction bearings 24 carried 40 by the shaft 26 of an intaglio or rotogravure cylinder 27, the antifriction bearings 24 being retained in predetermined spaced relation on the shaft 26 by suitable spacers 28. When the antifriction bearings 24 which are carried by the 45 cylinder shaft 26 are received within the yokes 20-21, the cylinder is then mounted for rotation in the machine frame, for a purpose to be herein-after explained. In conformity with the usual practice, an arm 30 is secured to the machine 50 frame 12, as best seen in Figure 3, and, this arm has a manually operable screw 31 threaded therein in axial alignment with the cylinder shaft 26 in order to engage the shaft and force the shoulder 25' of one of the antifriction bearing annular supports 25 against the inner ring of the antifriction bearing to thereby hold the cylinder 27 in predetermined axial position in the machine frame, the screw 31 being locked in fixed position by a manually operable lock or jamb nut 32. 60 This structure and its function are well understood by those skilled in the art and is disclosed in detail in the Springstead Patent No. 1,832,255.

As best shown in Figures 3 and 12 the shaft 26 of the intaglio, rotogravure or photogravure 65 form cylinder 27 has an axially extending reduced portion 33 provided to receive thereon a clamping sleeve 34 having axial slots 35 extending inwardly from each terminal thereof. The inner terminal of the sleeve is provided with an enlarged annular beveled or frusto conical head 36, and the opposed terminal of the sleeve 34 is externally threaded, as indicated at 37, for the reception of the threaded portion 38 of an annular clamping nut 40. The bore of the clamp- 75

ing sleeve 34 is provided with a featherway 41 for the reception of a key or feather 42 which is also received in a featherway formed in the reduced portion 33 of the cylinder shaft 26 to thereby hold the clamping sleeve 34 in predetermined angular position relative to the shaft 26 and its cylinder 27. An index or cylinder drive wheel 43 is provided, and this wheel includes a rim portion 45 supported by a hub 46 through interposed spokes 47. The hub 46 is in the form of a short cylinder having the inner portion of its opposed terminals beveled to provide frusto conical surfaces 48. The cylindrical hub 46 has its inner surface or bore dimensioned to be received or mounted on the outer peripheral surface of the clamping sleeve 34, and the frusto conical surface 48 formed at one terminal of the hub 46 engages the frusto conical head 36 of the sleeve 34, and the frusto conical surface 48 formed at the opposed terminal of the index wheel hub 46 is engaged by the outer surface of a frustoconical clamping wedge or ring 50 which is mounted on the outer peripheral surface of the clamping sleeve 34 and positioned to be engaged by the clamping nut 40. As best shown in Figure 3, a bracket 51 is secured to the machine frame 12 at the side of the machine which is remote from the arm 30, and the upper terminal of the bracket has a cylindrical stud 52 rigidly secured thereto, as indicated at 53. The stud 52 is positioned adjacent to and in axial alignment with the cylinder shaft 26 when the shaft 26 is operably positioned in the machine frame. When the index or cylinder drive wheel assembly is not in use on the cylinder shaft it is supported on the stud 52, in conformity with the usual practice.

When it is desired to secure the index wheel assembly to the cylinder shaft 26, the featherway 41 of the clamping sleeve 34 is positioned in correct angular relation to align with the feather or key 42, and then the assembly is slid axially from the stud 52 onto the reduced portion 33 of the cylinder shaft 26. After the index wheel assembly has been positioned on the reduced portion 33 of the cylinder shaft 26, a lever or wrench bar 55 is positioned in one of the radial wrench receiving openings 56 formed around the peripheral portion of the clamping nut 40. The clamping nut 40 is then screwed towards the frustoconical head 36 of the clamping sleeve 34, thereby causing the frustoconical clamping wedge 50 to engage the outer frustoconical surface 48 of the index wheel hub 46, and the frustoconical head 36 to engage the opposed or inner frustoconical surface 48 of the hub 46. Continued angular movement of the clamping nut 40 on its receiving threads 37 forces the opposed slotted terminals of the yieldable clamping sleeve 34 to locking engagement with the reduced portion 33 of the cylinder shaft 26, thereby securely locking the index wheel 43 to the cylinder shaft 26. The rim portion 45 of the index wheel is provided with a plurality of index apertures 57 positioned in predetermined angular relation therearound for a purpose which will be hereinafter explained.

In order to inscribe suitable register marks on the peripheral surface of the printing cylinder 27, a rail 58 is supported by the machine frame 12 and extends longitudinally thereof and parallel with the axes of the printing cylinder 27. This rail slidably supports a marker head or slide 60, which, in turn, supports a marker holder 61 having its outer terminal radially offset at 62, and the outer terminal of the offset portion 62 has a suitable marking tool 63 secured thereto. The

holder 61 is arranged to be turned through an angle of 90°, so that in the position indicated in Figure 1 of the drawings, the marking tool 63 is located below a horizontal plane passing through the axes of the form cylinder 27, and, when the holder is turned 90° from this position, the marking head 63 is placed back of or in trailing relation to the axes of the holder 61, for reasons to be hereinafter disclosed. Otherwise, the marker head or holder arrangement is similar in construction and operation to the marking device disclosed in the Springstead Patent No. 1,832,255 and the Friess Patent No. 2,074,218. The marker head or slide 60 is held in predetermined position along the rail 58 by a spring-pressed register pin or plunger 65 which is constructed and arranged in the manner disclosed in the above identified patents, so that its lower terminal will snap into engagement with the selected locating aperture 66 formed in the rail 58. By this arrangement the marking tool 63 of the holder 61 may engage any selected point axially along the cylinder surface.

To inscribe circumferential marks around the peripheral surface of the cylinder, in conformity with the usual practice, the holder 61 is turned to vertical trailing position best shown in Figure 1, and the marker head 60 is located in selected axial position along the cylinder by the engagement of the pin 65 with the selected aperture 66, as hereinbefore disclosed. Then the index wheel assembly is moved from the supporting stud 52 onto the reduced portion 33 of the cylinder shaft 26. In this position the clamping nut 40 is turned thereby securely clamping the index wheel to the cylinder shaft, as hereinbefore disclosed. This wheel may now be turned by hand in a clockwise direction, as viewed in Figures 1 and 2, thus causing the marking tool 63 of the holder 61 to inscribe circumferential marks on the peripheral surface of the cylinder.

When it is desired to inscribe axial marks on the peripheral surface of the cylinder 27, a register pin or plunger of construction and arrangement similar to the pin 65, is supported by a bracket 67 which extends from the machine frame 12, and this pin engages the selected aperture 45 to thus lock the index wheel 43 and cylinder 27 in predetermined angular position, as disclosed in the above identified patent. The marker head 60 is then slid along the rail 58, with the marking tool 63 positioned to trail the axis of the holder 61 and in marking engagement with the peripheral surface of the cylinder 27, thus causing the tool 63 to accurately inscribe axial register marks on the cylinder surface, in conformity with the conventional practice.

It has been found that in the operation of marking devices in which the stylus is positioned radially with respect to the cylinder surface and in alignment with its supporting component, that there is a tendency of the marking tool or stylus to vibrate or chatter during its operation. By offsetting the marking tool 63 relative to the axes of the holder 61, the marking tool 63 trails the holder axis when inscribing axially-extending lines along the peripheral surface of the cylinder 27, thus preventing chatter or vibrating action, so that a uniform line is accurately inscribed. Again, by offsetting the marking tool 63 with respect to the axes of the holder 61 and turning it so that the marking tool 63 is positioned below the axes of the engaged cylinder, then the axis of the marking tool is positioned at an angle

to the cylinder periphery, and when the cylinder is rotated clockwise the marking tool 63 circumferentially trails the axes of the holder 61, thus preventing vibratory action or chattering of the marking tool while circumferential register or locating marks are being inscribed on the peripheral surface of the cylinder 27.

In order to secure the usual sensitized backed carbon tissue upon the peripheral surface of the cylinder 27, a pressure or squeegee roller 68 is provided to operably cooperate with the cylinder. The opposed terminals of the supporting shaft 70 of the roller 68 are rotatably mounted in bearings 71 formed at the outer terminal of arm sections 72. Each arm section 72 is slidably or adjustably secured to an arm 73 by bolts or other securing members 75 which extend through apertures formed in the arm sections 72 and through longitudinal slots 76 formed in the arms 73. An arm 73 is pivotally secured at each side of the machine frame by keying its inner terminal to a stub shaft 77, as indicated at 78, in Figure 3, and each stub shaft is journaled in a bearing 80 formed in the uprights 19 of the frame superstructure. The arms 73 are preferably located at the inner sides of the uprights 19, and each stub shaft 77 extends through the bearing 80 and is keyed at its outer terminal to a short arm 81, as indicated at 82, thus causing the arms 73, stub shafts 77 and short arms 81 to turn or move in unison. The outer terminal of each short arm 81 is bifurcated, as indicated at 83, to receive the lower terminal of a link 85, and this terminal of the link 85 is slotted, as indicated at 86, to receive a pin 87 which extends through this slot and the furcations of the short arm 81. Each link 85 is provided with a turn buckle 87, so that its length may be adjusted, and the upper terminal 88 of each link 85 is pivotally secured 40 to the bifurcated terminal 90 of a lever 91. Each lever 91 is fulcrumed to the machine frame by securing the lever to a stub shaft 93 by a key or other suitable securing device 94, and the stub shaft 93 extends through a bearing 95 formed in an upright 19 of the machine frame. The inner terminals of each stub shaft 93 is keyed or otherwise rigidly secured to a short bifurcated arm 96, as indicated at 97, and the upper terminal of each link 98 is pivotally secured to each arm 96, as indicated at 100. Each link 98 extends downwardly from the arm 96, and has its lower terminal pivotally secured to a short lever 101, as indicated at 102 (Figure 1), and a suitable turn buckle 99 is carried by the link 98 in order that the length of the link may be adjusted. The upper terminal of each lever 101 is keyed or otherwise secured to a shaft 103 which extends transversely across the machine and is mounted for rocking movement in bearings 105 formed in the machine frame 12, best shown in Figure 3, so that the levers 101 and the shaft 103 rock or oscillate in unison. A link 106 (Figure 1) is pivotally secured to each lever 101 intermediate the terminal of the lever 101, as indicated at 107, and the opposed terminal of each link 106 is offset, as indicated at 108, and the offset terminal 108 is pivotally secured to an arm 110, as indicated at 111. Each arm 110 is rigidly secured to and carried by a shaft 112 which extends 70 transversely across the machine and has its opposed terminals mounted for rocking movement in bearings 113, best shown in Figure 3 of the drawing. Spaced treadle arms 114 are keyed or otherwise rigidly secured to a shaft 112, and these treadle arms 114 have a treadle bar 115

keyed or otherwise rigidly secured thereto, so that the treadle bar 115, treadle arms 114, shaft 112 and arms 110 oscillate or rock in unison. In order to limit the downward movement of the treadle bar about its fulcrum shaft 112, stop members 116 are positioned in the path of travel of the treadle bar 115, so that when the bar 115 engages the arcuate upper terminal 117 of each stop member 116, the downward movement of the bar 115 about the axis of its fulcrum shaft 112 is thereby stopped, for reasons to be herein-after explained. Each lever 91 has a counter-weight 118 slidably mounted for adjustment thereon, and each weight 118 is held in predetermined position on the lever 91 by a screw 15 or other suitable locking device 120. In order to manually move the pressure or squeegee roller 68, arms 121 extend from the arm sections 72 outwardly beyond the periphery of the roller 68, and these arms rigidly support a manipulating bar 20 122 which extends transversely across the machine between the uprights 18 to afford a ready gripping bar for the operator when he desires to move the squeegee roller by hand, as will be explained more in detail hereinafter.

During phases of the operation of the machine, it is desirable to conveniently develop the image producing portion of the form cylinder surface and to also etch the surface, as will be more fully explained hereinafter, and to this end 30 a composite reversible fountain or tray structure 123 is provided. This fountain or tray structure is of rectangular configuration and includes side walls 125 and end walls 126. Interposed between the side walls 125 and the end walls 126 is a 35 partition 127 which is disposed at an angle with relation to the side walls 125 and also at a lesser angle with relation to the end walls 126, so that the partition 127 forms a common angularly-disposed bottom which slants in two directions to 40 define and separate opposed fountain receptacles or trays 124. An outlet orifice 128 is formed at a corner of each fountain or tray at the lowest portion of the bottom of each fountain when in upright position, and an outlet tube 130 leads 45 from each orifice 128 through the adjacent receptacle, as best seen in Figures 1 and 9. The reversible fountain unit or structure is formed in any suitable manner, such as casting, or, preferably by welding its components together, as 50 indicated in Figure 9. In order that a suitable acid or etching material may be retained in the fountains or trays, each fountain receptacle or tray 124 is lined throughout with rubber or other acid resisting material 129, and the rubber lining 55 129 is so formed as to present a relatively heavy fillet of large radius at each corner or sharp angle portion within each fountain or receptacle. The inner portion of each outlet tube is also rubber lined, as indicated at 131, and the terminal of 60 the tube lining 131 which is positioned immediately adjacent the outlet orifice 128 of each fountain is beveled to define a frusto conical stopper seat 132, and the marginal edge of the fountain or tray walls are protected by extending the rubber lining 129 over these edges and partly over the outer surface of the side and end walls 125 and 126, as indicated at 129'. The fluid is held in the uppermost fountain receptacle or tray by a cylindrical overflow or stopper tube 70 133 which has its lower outer portion beveled to define a frusto conical surface 134 which is shaped and dimensioned to accurately engage the frusto conical stopper seat 132. When the overflow or stopper tube 133 is positioned in 75

the stopper seat 132 of the uppermost fountain receptacle, the upper terminal of the stopper tube 133 extends to a point adjacent the top of the fountain, so that the level of the fluid 5 within the uppermost fountain cannot rise above the top of the inserted stopper tube 133. After the stopper tube 133 has served its purpose as a stopper, it may be removed from the seat 132, thus permitting the fluid to flow downwardly 10 from the uppermost fountain receptacle through the seat 132 and the rubber lined tube 130. Each end wall 126 of the double or composite fountain structure has an inwardly extending enlargement or boss 135 formed on or secured thereto, and 15 each boss is provided with a bore or aperture 136 for the reception of a trunnion or bearing pintle 137. The aperture 136 and trunnion 137 located at one end of the fountain is positioned to axially align with the trunnion 137 located at 20 the opposed end of the fountain, so that each trunnion may be rotatably received in a bearing aperture 138 formed in a bearing block 140. Each bearing block 140 is mounted for vertical sliding movement between slide members or ways 25 141 carried by the machine frame 15. By this arrangement the double fountain unit 123 is mounted for vertical sliding movement along the slide and guide ways 141, and for rotary movement about the axes of its trunnions 137. One 30 of the sliding bearing blocks 140 is provided with a manually operable screw pin 142 which is threaded to the block 140 in a position so that the terminal of the screw pin 142 engages one of diametrically opposed apertures 143 formed in 35 the enlargement 135 carried by the end wall 126 of the fountain, to thereby lock the selected fountain receptacle in uppermost position.

In order to raise and lower the fountain unit 123 to permit the reversal of the fountains, a 40 lever 146 is provided having a manipulating handle 147, and this lever is keyed or otherwise rigidly secured to a shaft 148 which extends transversely across the machine and is mounted for rotation in bearings 150 carried by the side 45 members of the machine frame 12. The shaft 148 also has an arm 151 keyed or otherwise secured thereto, and the lever 146 and arm 151 are pivotally secured to the lower terminals of links 152, as indicated at 153, and the upper terminal 50 of each link 152 is pivotally secured to a bearing block 140, as indicated at 154. Each outer terminal of the shaft 148 has an arcuate arm 155 keyed or otherwise rigidly secured thereto, and the lower terminal of each arm 155 is bifurcated 55 to pivotally receive a terminal of a helical spring 156, as indicated at 157. The opposed terminal of each spring 156 is pivotally secured to an adjusting head 158 having a threaded stem 160 extending therefrom which extends through an aperture 161 formed in a bracket 162 secured to 60 the machine frame 15, and this stem 160 is secured in adjusted position to the bracket by means of adjusting and locking nuts 163.

By this arrangement, when the manipulating 65 handle 147 of the manipulating lever 146 is moved upwardly or downwardly, the lever 146, shaft 148, lever 151, links 152, slide bearing blocks 140, and reversible fountain unit 123 all move upwardly or downwardly in unison, and after 70 the springs 156 have been adjusted to exert sufficient tension to counter balance the weight of the reversible fountain unit 123 and its operating component, the entire assembly operates in balanced condition. As will be hereinafter 75 closed, the uppermost fountain or tray is to be

positioned adjacent the peripheral portion of the form cylinder 27, and in order that the fountain may be correctly positioned relative to the peripheral surfaces of cylinders, of different diameters, a plurality of apertures 161 are formed in a bracket or boss 162 carried by a side member of the machine frame 12 for the reception of a securing locking pin 163 which extends through the lever 146, thereby securely locking the lever 146 to the machine frame. 10

In conformity with the usual practice in machines of this character, a hood 166 is supported at the upper portion of the machine frame above the fountain 123 and impression cylinder 27, and this hood is connected with the usual ventilating 15 system to exhaust acid fumes, but, inasmuch as this arrangement is well understood by those skilled in the art no further description of it will here be given.

In order to secure each movable hinged yoke member 21 to a rail 17, a quick locking device 23 is provided for each movable hinged member. Each quick locking device (Figure 5) includes a cylindrical bolt 165 which extends through a cylindrical aperture 166 and an enlarged axially-25 aligned cylindrical recess 166' formed in a clamping foot 21' extending from the lower terminal of each hinged yoke member 21. The upper terminal of each bolt 165 is secured to a cylindrical head or hub 167 by a pin or stud 168 that extends through the head 167, bolt 165 and the inner terminal of a handle 170 which is received in a slot 171 extending transversely through the head or hub 167, and also in a slot 172 extending transversely through the upper portion of the 35 bolt 165, thereby securing the bolt 166, head 167, handle 170 together to move in unison. Each head or hub 167 is rotatably received in a circular aperture 173 formed in the upper face of the clamping foot or extension 21' of the hinged 40 yoke member 21. The lower terminal of the bolt 165 is enlarged and threaded, as indicated at 175, and this enlarged threaded portion 175 has its opposed sides cut away (Figures 6 and 7) as indicated at 176, to thus define an enlarged rectangular 45 threaded bolt terminal for locking engagement with a cylindrical locking nut 177. Each cylindrical locking nut 177 is provided with axially extending internal threads 178, and diametrically opposed grooves or recesses 180 interrupt the internal threads 178 to define a rectangular aperture for the reception of the rectangular threaded locking terminal of the bolt 165 during a phase of the operation of this bolt. Each cylindrical nut 177 is secured in the rail 50 portion 17 of the machine frame 12 by a threaded bolt or screw 181 which is threadedly received in the lower terminal of the locking nut 177, thereby 55 rigidly securing the nut 177 in the rail portion 17 of the machine frame 12, and if desired a key 60 or feather may be inserted between the nut 177 and the machine frame 12 to further hold the nut against turning in its seat aperture. A recess or bore 182 is formed in each hub or head 167 around the bolt 165 for the reception of a helical 65 spring 183. The upper terminal of this spring engages the hub or head 167 and its lower terminal engages the face of the circular aperture 173 formed in the locking foot or extension 21' of the movable yoke member 21. 70

After the antifriction bearing members 24 carried by the shaft 26 of the cylinder 27 are accurately positioned in the fixed yoke members 20, the hinged yoke members 21 are closed around the bearings 24. Each bolt 165 is then thrust 75

inwardly so that its rectangular locking terminal 175 is received within the rectangular aperture of the nut 177. Then each handle 170 is manipulated to turn the bolt 165 through an angle of 5 90°, so that the threads 176 of the locking bolt 165 engages the threads 178 of the locking nut 177 to securely lock the foot or extension 21' of the movable yoke member 21 to the rail 17 of the machine frame 12. In this position, the spring 10 183 is compressed to thereby exert tension against the hub or head to securely hold the locking components in locked position. To unlock the foot of the movable yoke members 21 from the machine frame 12, the bolt 165 is merely 15 given a quarter turn, thus moving the threads 176 of the bolt 165 from engagement with the threads 178 of the nut 177.

In operation, after the cylinder shaft 26 has been clamped in the yokes 20—21, the cylinder 20 may be freely rotated on its antifriction bearing 24. The peripheral surface of the cylinder may then be inscribed with suitable longitudinal and circumferential register or locating marks which 25 register with suitable marks formed on the marginal portion of the usual carbon tissue to indicate the accurate location of the tissue on the cylinder surface.

In applying the backed sensitized carbon tissue 30 S to the peripheral surface of the form cylinder 27, the squeegee or pressure roller 68 is brought into engagement with the backed carbon tissue positioned on the peripheral surface of the cylinder 27 in conformity with the usual practice, as disclosed in the hereinbefore identified Friess 35 patent. In order to lower the pressure or squeegee roller 68 from the position indicated in Figure 1 to operable engagement with the tissue positioned on the peripheral surface of the form cylinder 27, the treadle bar 115 is pushed downwardly by the foot of the operator until it engages the arcuate stop surface 117. During the downward movement of the treadle bar 115, the outer terminals of the arms 110 move downwardly and outwardly, thereby pulling outwardly on the links 106, which, in turn, rock the levers 101 about their fulcrum shaft 103 to pull downwardly on the links 98 to thus lower the squeegee roller 68, as hereinbefore disclosed. After the squeegee roller 68 has been lowered to engagement with the carbon tissue on the peripheral surface of the form cylinder 27, continued downward movement of the treadle bar 115 causes the lower terminals of the slots 86 formed in the lower terminals of the links 85 to move from engagement 50 with the pivot pin 87, thus operably disconnecting the squeegee roller 68 and its supporting mechanism from the counterbalancing effect of the weights 118, so that the full weight of the roller 68 is exerted against the peripheral surface of the cylinder 27 or the tissue thereon, to thus aid in securing the tissue to the surface of the cylinder in conformity with the usual practice well understood by those skilled in the art. When the treadle bar 115 is approaching its lowermost position, the outer terminals of the links 106 move downwardly past a plane extending through the link pivots 107 and the arm fulcrums 112, to thus hold the components which are operated by the treadle bar 115 in their lowermost position with the full weight of the squeegee roller resting upon the tissue positioned on the peripheral surface of the form cylinder 27. If desired, this toggle action may be employed to impart downward stress to the squeegee roller in addition to the normal gravitational force. 55 60 65 70 75

The length of the slots 86 may be so proportioned and the turn buckles so adjusted that as the toggle arms 110 approach the center position, hereinbefore defined, the top of the slots 86 will engage the pins 87 thus pressing down on the 5 short arms 81 thereby imparting downward stress to the squeegee roller 68 through the interposed mechanism hereinbefore disclosed. To facilitate the movement of the squeegee or pressure roller 68, a handle bar 122 carried in the outer terminals of the arms 121 is provided, whereby the roller may be delicately lowered into engagement with the cylinder.

In applying the backed sensitized carbon tissue to the peripheral surface of the form roller 27 15 it is desirable, in conformity with the usual practice, to wet the surface of the sensitized tissue which is positioned towards the cylinder 27 without wetting its supporting backing. As disclosed in the hereinbefore identified Friess patent, the backed tissue sheet S is secured to the cylinder surfaces by a securing tab or tape, as indicated in Figure 15, and the tissue sheet is placed over the squeegee roller 68 with the greater portion of it being suspended from the roller. 20 As shown in Figure 15, the roller 68 is positioned to engage the backed tissue which is supported by the surface of the cylinder 27 at a point to one side of a vertical line passing through the axis of the form cylinder 27. Water is then 25 supplied through a hose or other convenient conveying instrumentality to the valley or trough V which is formed by the peripheral surface of the cylinder 27 and the sensitized surface 30 of the tissue sheet which is supported on the squeegee roller 68. As the roller rotates clockwise, as viewed in Figure 15, the supplied water is retained in the valley V and pushed ahead of the squeegee roller, thus thoroughly wetting the inner face of the tissue and form cylinder surface 35 so that the tissue may be secured to the cylinder surface. It will be understood that by adjustment of the arms 73, the amount of water held between the roller 68 and the cylinder may be varied as desired. 40 45

After the sensitized carbon tissue has been accurately positioned on the cylinder surface in conformity with the usual practice, as disclosed in the hereinbefore identified Friess patent, the supporting back of the carbon tissue is then removed leaving the sensitized tissue on the peripheral surface of the form cylinder 27. Assuming that the manipulation handle 147 of the lever 146 is secured in its uppermost position with one of the trays or fountains positioned and secured immediately below the cylinder 27, a suitable quantity of developing fluid is then placed in the tray or fountain. The cylinder 27 is then rotated in the developing fluid through the instrumentality of a motor drive which preferably engages the rim 5 of the index wheel in the manner disclosed in the hereinbefore identified Friess patent. Inasmuch as the motor drive does not form a part of this invention and has been disclosed in the Friess patent, and is well understood by those skilled in the art, the drive is not illustrated in this application. After the developing operation, the uppermost tray or fountain receptacle is drained by removing the overflow and stopper plug or tube 133. This developing 50 fluid may be discharged into the basin 14 formed in the base 13 of the machine and from there conveyed to any suitable destination in the draining system, in conformity with the usual practice, or, if preferred, this fluid may be col- 55 60 65 70 75 80 85 90 95 98

lected in a receptacle placed below the fountain outlet. The uppermost fountain tray or receptacle is then preferably washed and drained preparatory to the employment of the etching fluid. After the uppermost fountain receptacle has been washed and drained, the fountain unit 123 is lowered by, first, removing the manipulating handle securing pin or screw 163, and, then, moving the lever 146 downwardly to the position indicated in Figure 2. The downward movement of the lever 146 causes the fountain unit 123 to move downwardly, as hereinbefore disclosed, and then the fountain unit is rotated to move the lowermost fountain to the upper position. The lever 146 is then returned to its original position, as indicated in Figure 1, thus positioning the then uppermost fountain receptacle or tray immediately below and partly around the peripheral surface of the form cylinder 27. A suitable acid-containing etching fluid is then flowed over the cylinder and is caught in the fountain tray or receptacle, the overflow or stopper tube 133 having been reinserted to prevent the escape of the etching fluid. After the etching operation, the stopper tube 133 is removed and the etching fluid is then drained into a container placed below the drain outlet, so that this fluid may be preserved for future use.

It will be understood that the invention may be embodied in other specific forms without departing from the spirit or essential attributes thereof, and it is therefore desired that the present embodiment be considered in all respect as illustrative and not restrictive, and it will be further understood that each and every novel feature and combination present in or possessed by the mechanism herein disclosed forms a part of the invention included in this application.

Having thus described my invention, what I claim as new and useful is:

1. In a device of the class described, means for rotatably supporting a printing cylinder which is operably rotatable to move its peripheral surface in a given direction, the said cylinder having liquid supplied thereunto, and a roller positioned to engage the upper peripheral portion of the cylinder at a point located at the side of a vertical plane passing through the axis of the cylinder towards which the upper portion of the cylinder periphery is moving to thereby form a fluid-holding valley between the cylinder and the roller.

2. In a device of the class described, means for rotatably supporting a printing cylinder which is operably rotatable to move its peripheral surface in a given direction, the said cylinder having liquid supplied thereinto, a roller mounted to coact with the printing cylinder to engage a sensitized tissue positioned on the peripheral surface of the cylinder, the roller engaging the tissue at a point located at the side of a vertical plane passing through the axis of the cylinder towards which the upper portion of the cylinder periphery is moving to define a fluid-holding valley between the highest portion of the cylinder and the portion of the tissue which is supported by the side of the roller.

3. In a device of the class described, means for rotatably supporting a printing cylinder which is operably rotatable to move its peripheral surface in a given direction, the said cylinder having liquid supplied thereunto, a roller mounted to coact with the printing cylinder, the roller being adjustably mounted to engage the upper peripheral portion of the cylinder at determined

points located at the side of a vertical plane passing through the axis of the cylinder towards which the upper portion of the cylinder periphery is moving to thereby form a fluid-holding valley between the cylinder and the roller.

4. In a device of the class described, means for rotatably supporting a printing cylinder which is operably rotatable to move its peripheral surface in a given direction, the said cylinder having liquid supplied thereunto, a roller rotatably supported by spaced pivotally mounted arms and the length of the arms being adjustable to operably position the roller to engage the upper portion of the cylinder surface at different points located at the side of a vertical plane which passes through the axis of the cylinder towards which the upper portion of the cylinder periphery is moving to thereby form a fluid-holding valley between the cylinder and the roller.

5. In a device of the class described, means for rotatably supporting a printing cylinder, a roller mounted to coact with the printing cylinder, means for moving the roller to and from engagement with the printing cylinder, means normally operably connected with the roller moving means to counterbalance the roller in its movement to and from the printing cylinder, and means for automatically disconnecting the counterbalancing means from the roller moving means when the roller engages the cylinder.

6. In a device of the class described, means for rotatably supporting a printing cylinder, a roller mounted to coact with the printing cylinder, means for moving the roller to and from engagement with the printing cylinder, means normally operably connected with the roller moving means to counterbalance the roller in its movement to and from the printing cylinder, and means operably connected with the roller moving means for imparting additional stress to the roller to be exerted against the cylinder surface.

7. In a device of the class described, means for rotatably supporting a printing cylinder, a roller mounted to coact with the printing cylinder, means for moving the roller to and from engagement with the printing cylinder, means normally operably connected with the roller moving means to counterbalance the roller in its movement to and from the printing cylinder, means for automatically disconnecting the counterbalancing means from the roller moving means when the roller engages the cylinder, and means operably connected with the roller moving means for imparting additional stress to the roller to be exerted against the cylinder surface.

8. In a device of the class described, means for rotatably supporting a printing cylinder, a roller mounted to coact with the printing cylinder, means for supporting the roller for movement to and from the printing cylinder, a foot-operable treadle movable through a predetermined path of travel, counterbalancing means, means for operably connecting the counterbalancing means, roller supporting means and said foot treadle whereby movement of the foot treadle moves the roller to and from engagement with the printing cylinder, the counterbalancing means counterbalances the roller during its movement to and from the printing cylinder, and means whereby the counterbalancing means is rendered inoperative when the roller engages the printing cylinder.

9. In a device of the class described, means for rotatably supporting a printing cylinder, a roller

- mounted to coat with the printing cylinder, means for supporting the roller for movement to and from the printing cylinder, a foot operable treadle movable through a predetermined path 5 of travel, a stop member to limit the downward movement of the said foot treadle, counterbalancing means, and means for operably connecting the counterbalancing means, roller supporting means and foot treadle whereby movement 10 of the foot treadle moves the roller to and from engagement with the printing cylinder, the counterbalancing means counterbalances the roller during its movement to and from the printing cylinder, and the foot treadle and said connecting means cooperating to impart additional stress 15 to the roller which is exerted against the surface of the cylinder when the foot treadle is in engagement with the stop member.
10. In a device of the class described, a frame 20 for rotatably supporting a printing cylinder, a marker head slidably parallel to the axis of the printing cylinder, a stylus rotatably supported by the printing cylinder, a marking tool supported in offset relation to the axis of the stylus 25 and adapted to engage the surface of the printing cylinder in trailing relation to the axis of the stylus when the marking head is moved relative to the cylinder and when the cylinder is moved relative to the marking head.
11. In a device of the class described, a frame 30 for rotatably supporting a printing cylinder, a marker head slidably parallel to the axis of the printing cylinder, a stylus rotatably supported by the printing cylinder, a marking tool supported to 35 offset relation to the axis of the stylus and adapted to engage the surface of the printing cylinder in trailing relation to the axis of the stylus when the marking head is moved axially relative to the cylinder, means for turning the stylus through an 40 angle of 90° to position the marking tool in trailing relation to the axis of the stylus circumferentially of the cylinder to thereby position the marking tool to one side of a horizontal plane 45 passing through the axis of the cylinder and in angular relation to the peripheral surface of the printing cylinder.
12. In a device of the class described, means for 50 rotatably supporting a printing cylinder and its supporting shaft, an index wheel having a hub portion, a clamping sleeve adapted to be mounted on the cylinder shaft, and means for simultaneously clamping the hub portion of the index wheel 55 to the clamping sleeve and the clamping sleeve to the cylinder shaft to thereby operably secure the index wheel to the shaft in any selected angular position.
13. In a device of the class described, means for 60 rotatably supporting a printing cylinder and its supporting shaft, an index wheel having a hub portion, a yieldable clamping sleeve adapted to be mounted against rotation on the cylinder shaft, and means supported by the clamping sleeve for movement relative thereto to simultaneously clamp the hub portion of the index wheel to the 65 clamping sleeve and the clamping sleeve to the cylinder shaft thereby rigidly securing the index
- wheel to the cylinder shaft in any selected angular position.
14. In a device of the class described, a printing cylinder, a supporting shaft for the printing cylinder, a reduced portion extending from the cylinder shaft, a slotted yieldable clamping sleeve adapted to be received on the reduced portion of the cylinder shaft, an enlarged frusto-conical head formed at one terminal of the clamping sleeve, means for securing the clamping sleeve 10 against rotation relative to the cylinder shaft, a clamping nut threadedly secured to the locking sleeve, a frusto-conical clamping wedge movably supported on the clamping sleeve and in engagement with the clamping nut, an index wheel, a 15 cylindrical hub for the index wheel having frusto-conical terminal seats, and means for turning the clamping nut relative to the clamping sleeve thereby forcing the clamping wedge into engagement with the clamping seat formed at one terminal of the index wheel hub and to force the frusto-conical head into engagement with the frusto-conical seat formed at the opposed terminal of the index wheel hub thereby locking the clamping sleeve to the reduced portion of the cylinder shaft and the hub to the clamping sleeve to rigidly secure the index wheel to the cylinder shaft for rotation therewith. 20
15. In a device of the class described, means for 25 rotatably supporting a printing cylinder which is operably rotatable to move its peripheral surface in a given direction, the said cylinder having liquid supplied thereunto, a roller positioned to engage the upper peripheral portion of the cylinder at a point located at the side of a vertical plane passing through the axis of the cylinder towards which the upper portion of the cylinder periphery is moving to thereby form a fluid-holding valley between the cylinder and the roller, and a fountain unit having a plurality of fountain receptacles mounted for positional reversal 30 below the cylinder whereby the selected fountain receptacle may be moved to a predetermined co-operable position relative to the cylinder. 35
16. In a device of the class described, means for 40 rotatably supporting a printing cylinder, which is operably rotatable to move its peripheral surface in a given direction, the said cylinder having liquid supplied thereunto, a roller mounted to 45 contact with the printing cylinder to engage a sensitized tissue positioned on the peripheral surface of the cylinder, the roller engaging the tissue at a point located at the side of a vertical plane passing through the axis of the cylinder towards which the upper portion of the cylinder periphery is moving to thereby form a fluid-holding valley 50 between the highest portion of the cylinder and the portion of the tissue which is supported by the side of the roller, and a fountain unit having a plurality of fountain receptacles mounted for 55 positional reversal below the cylinder whereby the selected fountain receptacle may be moved to a predetermined co-operable position relative to the cylinder to permit the fountain contents to engage the cylinder periphery. 60

WILLIAM F. HUCK.
